UNITED STATES PATENT OFFICE.

WILLIAM E. WINE, OF TOLEDO, OHIO.

CAR-DOOR LOCK.

Application filed May 5, 1921. Serial No. 467,004.

To all whom it may concern:

Be it known that I, WILLIAM E. WINE, a citizen of the United States, residing at Toledo, in the county of Lucas and State of Ohio, have invented certain new and useful Improvements in Car-Door Locks, of which the following is a specification.

This invention relates to door-locking devices for railway cars or the like and has for its object to provide improved means for holding the doors in closed position, the arrangement being such as to be readily released when it is desired to open the doors. Another object is to provide simple means for locking or unlocking a plurality of doors at one and the same time by means of a common mechanism. With such objects and others in view the invention consists of the formation, combination and arrangement of parts as will be herein described and particularly claimed.

In the accompanying drawings which show a preferred embodiment of the invention, Figure 1 is a side elevational view of a portion of a car body, this view showing particularly the lower corner of the hopper portion of a car of well known type. Figure 2 is a fragmentary elevational view of the same, this view being seen in the direction of the arrow 2, Figure 1. Figure 3 is a transverse sectional view taken through the hoppers of one end of such a car, the view being taken approximately on a plane indicated by the line 3-3 of Figure 1 and showing the locking mechanism of the present invention in its relationship to the car doors and other portions of the car body. Figure 4 shows, in a view similar to Figure 3, a modified application of the mechanism, wherein each of the pair of doors is locked independently and at the center as well as at the sides of the car. Figure 5 is a diagrammatic view of the side of a car, showing the general arrangement of doors such as are used for reference in Figures 1 to 4.

Referring to these drawings, the side of the car or the side of the hopper is denoted by the numeral 1, the bottom of the hopper being denoted by the numeral 2. The hopper as shown is that commonly employed on cars of the twin hopper type, having the hopper floor 2 inclined to form a chute for the discharge of the contents by gravity. Such hoppers are ordinarily provided at each end of the car and there are customarily two such hoppers at each end arranged side

by side as indicated at 3 and 4 in Figure 3 and at 5 and 6 in Figure 4. The inner sides of these hoppers are defined by hopper sheets 7, with an intervening space which customarily results from the center or draft sill construction of the car.

Each of the hoppers is closed by means of a door 8, these doors being set upon an inclined plane substantially at right angles to the plane of the bottom of the hopper or chute plate 2. The doors are hinged or pivoted along their upper edges at 9 to the car body, the free edges 10 of the doors being arranged to swing away from the open ends of the chute plates 2 when the doors are to be opened. No special mechanism is provided for the mechanical swinging of the doors into closed positions as it has been found that if the doors are properly fitted they can be swung by hand. It is the object of the invention to provide improved means for locking the doors after they are closed manually and to this end a bracket 11 is secured to the side of the hopper by means of rivets 12. This bracket has a staple or other hook-engaging member 13 affixed to it and the door carries a pivoted locking member in the form of a hook 14 which is arranged to latch over the staple 13 when the doors are pulled shut, thus holding the door in closed position without the intervention of any unnecessary parts. When the hooks 14 are in holding position the dog 15 which is made in cam shape and pivoted to the bracket 11 by means of a rivet 16, is rotated about its pivot so as to contact the point 17 of the hook and prevent the accidental release of the same. Formed integral with the cam 15 and on the opposite side of the pivot 16 is an extension 18 which is provided for forcing the eccentric cam into or out of hard engagement with the point 17 of the hook 14.

The present device is so arranged that a plurality of locking hooks may be so arranged transversely of the car or otherwise in line with each other, that they may be operated together from a single point and as a single unit. Thus in Figure 3 one hook outfit is shown along each side of the car with a bracket and staple for each hook. The hooks are connected by a shaft 19 which extends across the car from side to side. This shaft is of square section and the hubs 20 of the hooks are formed with square apertures so that they will be held against rota-

tion when mounted upon the shaft as shown. Accordingly when the shaft is rotated from one end by means of a wrench or other tool, all of the hooks upon the shaft will be rotated with it and the hooks may thus be lifted out of engagement with the staples 13. On closing the doors the inclined faces 21 of the hooks will cause them to automatically lift themselves, rotating the shaft 19, the hooks dropping into positions within the staples 13. The shaft 19 as before stated is carried by the door and in the construction shown in Figure 3, it embraces the pair of doors for the pair of hoppers at one end 15 of the car. The shaft thus serves as an aligning and supporting means for the doors and prevents them from bulging or bending due to the pressure of the lading against them.

20 Such doors are often provided with outward turned marginal flanges such as shown in the drawings in order to stiffen the edges of the doors. Because of the presence of such flanges it is necessary that the shaft 19 be 25 spaced away from the backs of the doors a sufficient distance to allow it to pass uninterruptedly and without weakening over the outermost edges of such flanges, inasmuch as the shaft replaces the ordinary door- 30 supporting beam or stiffener. This arrangement of the shaft, considered as a stiffener, is one of the objects of the invention.

In order that the shaft may be properly carried upon the doors, brackets 22 are affixed 35 to the doors by means of the rivets 23, these being affixed to the faces of the door plates away from the cavity of the car. These brackets have cylindrical apertures which accommodate cylindrical spools 24 which are 40 fitted upon the shaft 19. The spools 24 have square apertures for their fit upon the shaft 19, hence the rotation is effected by the spools 24 revolving within the brackets 22. Each spool 24 has a collar 25 of slightly larger 45 diameter than the bore of the bracket 22 and these collars overlie the hubs of the brackets to prevent endwise movement of the shaft 19 and the parts carried by it. The collars of some of the spools are arranged to prevent 50 movement in one direction and the collars of others to prevent movement in the opposite direction. Cotter pins 26 are applied in holes suitably drilled in the shaft 19 to retain the collars and the hooks against 55 movement on the shaft. An extension 27 is formed upon the hook 14 in a position on the opposite side of the axis thereof from the locking face of the hook and this may be utilized for forcing the hook out of engagement with the staples in case a wrench is 60 not available for the shaft 19.

In the modification shown in Figure 4 two hooks are used for each of the doors at an end of the car, there being hook outfits on 65 the inturned faces of each of the interme-

diate chute hopper sides 7. One shaft 28 extends inward from the side of the car to near the center and each such shaft carries a pair of hooks 14, one near each end of the shaft. In this manner the door 8 may be 70 locked along each edge instead of along one edge as in the arrangement shown in Figure 3. The arrangement of the bracket 11 with the staple 13, as well as of the brackets 22 and spools 24, is the same as previously 75 described for the construction of Figure 3, the only difference being that the two hooks on a common shaft in this case serve only one door whereas in the preceding case they served a pair of doors. The dogs 15 for the 80 interior hooks in this arrangement may or may not be used. When they are used a specially formed unlocking tool is used for their actuation.

I have thus described a preferred embodiment of my invention. Other embodiments are contemplated within the scope of the appended claims, without departing from the spirit thereof:

What is claimed is:

1. In a door mechanism for railway cars, a door pivoted to the car body, a shaft rotatably mounted upon the door, a door-supporting hook rigidly secured to the shaft, and a hook-engaging member carried by the 95 car body in position to be engaged by the said hook when the door is closed.

2. In a door mechanism for railway cars, a door pivoted to the car body, a shaft rotatably mounted upon the door, a door-supporting hook rigidly secured to the shaft, and a hook-engaging member carried by the car body in position to be engaged by the said hook when the door is closed, the hook being engageable or disengageable with the 105 said hook-engaging member upon rotation of the said shaft.

3. A railway car having a pair of hoppers arranged side by side, discharge openings from the said hoppers, the same being also arranged side by side, a door for each of said openings, the same being hinged to the car body at one edge of their respective openings, a shaft extending along both of said doors and mounted in rotatable fashion 115 thereupon, a plurality of door-supporting hooks rigidly secured to the shaft and rotatable therewith, and a corresponding number of hook-engaging members affixed to the car body and arranged for cooperation with the said hooks, the hooks being engageable or disengageable with the said members upon rotation of the said shaft.

4. A railway car having a hinged door, a shaft rotatably mounted upon the door, a plurality of door-supporting hooks rigidly affixed to the shaft and rotatable therewith, a corresponding number of hook-engaging members carried by the car body, the said hooks being engageable or disengageable 130

with the said hook-engaging members upon rotation of the said shaft, and means for preventing accidental rotation of the shaft, the same cooperating between the car body 5 and one of the hooks.

5. In a door mechanism for railway cars, a door pivoted to the car body, the same having a marginal out-turned flange, a door-stiffening member extending across the outer 10 face of the door and projecting beyond the

edge thereof carrying the marginal flange, door-supporting means cooperable between the projecting end of the stiffening member and the side of the car, the said stiffening member being spaced away from the outer 15 face of the door, a sufficient distance to clear the said marginal flange.

In testimony whereof I affix my signature.

WILLIAM E. WINE.
